UNITED STATES PATENT OFFICE.

EDGAR GOOD, OF KALAMAZOO, MICHIGAN, ASSIGNOR TO KALAMAZOO SPRING & AXLE COMPANY, OF KALAMAZOO, MICHIGAN, A CORPORATION OF MICHIGAN.

AXLE-SKEIN.

SPECIFICATION forming part of Letters Patent No. 694,681, dated March 4, 1902.

Application filed April 27, 1901. Serial No. 57,750. (No model.)

To all whom it may concern:

Be it known that I, EDGAR GOOD, a citizen of the United States, residing at Kalamazoo, in the county of Kalamazoo and State of 5 Michigan, have invented certain new and useful Improvements in Axle-Skeins, of which the following is a specification, reference being had therein to the accompanying drawings.

- The invention relates to axle-skeins, and has for its object the obtaining of a skein in which a durable wearing-surface is combined with a structure which materially strengthens the axle.
- 15 Heretofore axle-skeins have been formed usually either entirely of cast metal or entirely of wrought metal and in some instances of a combination of cast and wrought metal. In these prior constructions where the skein 20 is formed either whole or part of wrought metal the wearing-surface of the skein has proven less durable than the cast skeins. This is for the reason that there is usually a greater thickness of metal in the wearing 25 portion of the cast skein than can be used in the wrought skein without materially increasing its weight and cost. Moreover, experience has demonstrated that cast metal has better wearing qualities for this particu- 30 lar use than wrought metal. On the other hand, where the skein is formed entirely of cast metal the structure is lacking in strength and is liable to fracture.

The present invention consists in the pecu- 35 liar construction of a composite skein in which the wearing portion is formed of cast metal and the structural portion, which is secured to the wooden axle, is formed of a combination of wrought and cast metal.

- 40 The invention further consists in the peculiar construction, arrangement, and combination of parts, as hereinafter described and claimed.

In the drawings, Figure 1 is a longitudinal 45 section through the axle-skein. Fig. 2 is a cross-section on line $\alpha\alpha$, Fig. 1.

A is the wearing portion of the skein or that portion upon which the hub of the wheel is journaled. This portion is of the usual

tapering form and is formed entirely of cast 50 metal. At its inner end it is provided with a shoulder B and a rearwardly-extending tubular shank C, which is also preferably of a tapering form.

D is the socket portion and tail of the skein, 55 which forms the connection with the wooden axle and which is of the usual form. This socket portion and tail is formed of wrought metal and is provided with a portion E, which is adapted to be shrunk upon the shank portion C of the cast section. At the inner end of the portion E is formed an enlargement F, which forms the ring or shoulder for the skein.

With the device as thus constructed when 65 the tail and socket D is secured to the wooden axle it will form a strong connection therewith and one which is not liable to fracture. The portion E, surrounding the cast shank C, will strengthen the latter to resist any strains, 70 and inasmuch as it is shrunk on the two parts are as securely attached as if formed integral. The bearing portion A of the skein is not subject to as great strains as the inner portion, and thus the cast metal will be of 75 sufficient strength, while the wearing-surface is much more durable than with the all-wrought construction.

The term "wrought metal" as used in the specification and claims is intended to denote the inherent qualities of the material forming one member which distinguishes it from that forming the other and is not used to designate the manner in which the member is formed. I therefore do not intend to 80 be limited to the member which in its formation is actually wrought, but only to one formed of metal having the essential characteristics of wrought metal—viz., freedom from brittleness and tenacity. 90

What I claim as my invention is—

1. An axle-skein comprising a journal or wearing portion formed of cast metal having an inwardly-extending integral shank and a shoulder formed between said shank and wearing portion, a tail and socket portion at the outer end thereof formed of wrought metal and having a sleeve at its outer 95

shrunk upon said inwardly-projecting shank and a shoulder or collar formed at the outer end of said sleeve and integral therewith.

2. An axle-skein comprising a journal or 5 wearing portion formed of cast metal having an inwardly-extending integral shank, a tail and socket portion formed of wrought metal and a sleeve formed integral with said tail and socket portion shrunk upon said shank

and having its inner end thickened to form to a collar adjacent to said wearing portion.

In testimony whereof I affix my signature in presence of two witnesses.

EDGAR GOOD.
